UNITED STATES PATENT OFFICE

PAUL H. GRANGER, OF LOS ANGELES, CALIFORNIA

MACHINE FOR FORMING ARROW SHAFTS

Application filed November 22, 1927. Serial No. 235,040.

This invention relates to a machine for forming shafts or elongated round bodies and the main object of the invention is to provide a machine which will rapidly and accurately 5 cut shafts of any desired shapes from suitable stock.

A further object of the invention is to provide a machine for this purpose which will enable the shape of the arrow cut there- 10 from to be varied at will.

The accompanying drawings illustrate em- bodiments of my invention and referring thereto:

Fig. 1 is a plan view of the machine.
15 Fig. 2 is a side elevation thereof.

Fig. 3 is an end elevation taken from the right hand end of Fig. 2.

Fig. 4 is a horizontal section of the arrow stock separating means showing the por- 20 tion of the cutter in operative position.

Fig. 5 is a section on line 5—5 in Fig. 4.

Fig. 6 is a section on line 6—6 in Fig. 4.

Fig. 7 is a diagrammatic section of the stock showing the relation of the cutter 25 thereto.

Fig. 8 is a partial section of the feed nut used to feed the stock forward.

Figs. 9 to 12 inclusive show different forms 30 of arrow shafts which may be cut by my machine.

The operative parts of the machine are mounted on a suitable base 1 which is adapted to be secured to any suitable support and is provided with bearings 2 in which is mounted 35 a shaft 3 for a cutter head 4, said shaft being also provided with suitable driving means such as pulley 5 adapted to be driven by any suitable driving connection.

A work carrier 7 is mounted to slide on 40 guide way 8 on the base 1 and is provided with means for supporting, rotating and feeding the stock or wooden strip out of which the arrows are to be formed. A bearing 10 is rigidly mounted on the carrier 7 and a hollow shaft 11 is mounted to rotate within 45 said bearing and is provided with suitable driving means such as pulley 12. Adjacent the inner end of the bearing 10 and between said bearing and the cutter 4 is provided a 50 collar 15 supporting a feed nut 16 which is

adapted to surround the arrow stock and to engage the same to feed the stock forward toward the cutter in the rotary movement of the stock. Said feed nut has a forwardly tapering base and thread therein, to permit 55 the stock to enter same. For convenience in construction the collar 15 may be made in upper and lower halves connected to one another and to the base 1 by cap-screws 18 and may be formed with square recesses 19 60 forming, when the parts of the collar are assembled, a square opening adapted to fit and hold in position the feed nut 16, the outside of which is rectangular in shape, as indicated, to fit said opening. Feed nut 16 is 65 preferably formed with ratchet threads, as shown in Fig. 8, so as to present flat faces at the front thereof, to provide for more effective feeding action. A collar 20 may be provided between the feed nut 16 and the 70 inner end of the hollow shaft 11 and adjacent its inner end said hollow shaft is provided with a square opening or passage 21 adapted to fit more or less closely the stock of which the arrows are to be formed. For 75 convenience in adapting the machine to stock of different sizes, said square opening is pref- 80 erably formed in a sleeve or liner 22 of rectangular cross-section secured by Babbitt metal or otherwise within an axial bore 23 in the shaft 11 so that such liner may be re- 85 moved and be replaced by another of different size if required. At its outer end the hollow shaft 11 is provided with a guide flange 24 which is bored as at 25 to fit the 85 arrow stock as shown in Fig. 3 and said flange may also be adapted to be removed and replaced to fit the particular stock which it is desired to use. At its inner end the hollow shaft 11 may be provided with a screw 90 thread 27 adapted to prevent grease work- 95 ing out of the bearing at that end.

Adjacent to the feed nut supporting collar 15 is provided a back rest or work support 28 rigidly secured on the work carrier 7, for ex- 95 ample, by cap screw 29. For convenience in aligning the various parts the bearing 10, collar 15, and work support 28 are preferably provided with key ways adapted to fit on a single key 30 extending on carrier 7 parallel

to the direction of arrow feed and transverse to the direction of movement of the work carrier. Said work support 28 is provided with a tapering recess 31 concaved as shown in Fig. 5 to approximately fit the arrow stock as it is being cut to shape and prevent undue springing of the stock under the pressure of the cutter. Said recess may be provided with a removable liner 32, so as to adapt it to different size arrows. Actual and accurate centralization of the stock, however, during the cutting operation is provided by the driving sleeve 22 and feed nut 16 at one side of the cutter and by a self-adjusting steady rest 10 supported on the back rest 28 at the other side of the cutter. Said steady rest is mounted within a recess 33 formed in the part 28 and having a conical or tapering face 34 against which seats a conical face 35 on a 15 steady rest collar 36. Said steady rest collar is held in position by means of a cap 37 secured by screws 38 to the part 28 and formed with a cylindrical portion 39 fitting over a cylindrical portion 40 of a follower plate 44 20 and containing a spring 41 engaging at one end with shoulder 42 on said cap and at the other end with the hub portion 40 of the follower plate 44 which is adapted to slide within a cylindrical recess 45 in the steady rest 25 collar. Said steady rest further comprises sliding jaws 46 which have convex inner faces 47 adapted to fit more or less closely the finished arrow shaft, said jaws being mounted to slide in a direction parallel to the axis 30 of the arrow shaft by engagement of said jaws in ways 48 formed in the steady rest collar 36 (see Fig. 6), said ways being convergent toward the cutter 4 and the respective jaws being provided with inclined 35 faces 48' engaging said ways so as to cause the jaws to move inwardly toward the axis of feed of the arrow stock as they are moved longitudinally parallel to the said axis by the 40 operation of spring 41. By the described construction the jaws 46 are enabled to grip and hold the arrow shaft at the delivery side of the cutter so as to maintain accurate centralization of the arrow shaft during the cutting operation, while at the same time said jaws 45 will yield automatically to accommodate variation in size of the arrow shaft as it enters said jaws by reason of variation in diameter of the arrow shaft from end to end as herein-after described.

50 The work carrier 7 is operated by any suitable means, for example by handle 49 on a shaft 51 mounted to turn in a bearing 50 on base 1 and provided with a screw portion working in a lug 52 on the work carrier 7 55 to move the work carrier toward or from the cutter.

The machine is intended to operate upon stock consisting of wooden strips of suitable cross-section, for example, square strips or 60 stock sections, indicated at 53, of sufficiently

large cross-section and sufficient length to enable the desired arrow shaft to be cut therefrom, and for convenience in feeding the stock into the machine and delivering the shafts therefrom, each stock section corresponding to a single arrow is preferably formed at each end with means for engaging or connecting it with a preceding or succeeding section, for example, by a wooden key, as indicated at 54 in Fig. 4. In the operation 70 of the machine a series or succession of stock sections are fed into the opening 25 and through the squared opening 21 and the feed nut 16 and the hollow shaft 11 being set in rapid rotation by the driving means 12, the 75 squared stock, which is in rotative connection with the hollow shaft by engagement with the squared opening 21, is caused to turn within the feed nut 16 and said feed nut engages the corners or edges of the stock so as 80 cut a screw thread on such edges, the portions so cut being indicated in dotted lines in Fig. 7, and also to cause the stock to operate as a screw within the fixed feed nut 16 by reason of the helical cuts so formed in the stock 85 section so that the stock is forced to feed forward in the direction of the arrow in Fig. 4 in such manner that its forward end passes in front of the cutter 4. In passing in front of the cutter which is set in rotation by driving 90 means 5, the stock is cut by a taper cut (the operation of the cutter on the stock being indicated in Fig. 7) so as to reduce its forward end to round cross-section sufficiently small 95 to enter and turn within the steady rest jaws 100 46, the advancing stock, in the case of the first stock section so entered, pushing the jaws back until the aperture between the same is enlarged sufficiently to enable the stock to enter. In the case of succeeding 105 stock sections, each section follows the preceding one immediately and the key connection 54 causes rotation of the preceding section by the succeeding section even after the preceding section has passed out of the 110 squared opening 21. Thus a continuous series of stock sections is fed through the machine by the rotation of the stock and the operation of the fixed feed screw 16. As each 115 stock section passes in front of the cutter the 120 operator by means of the handle 49 operates the work carrier 7 toward or from the cutter so as to increase or decrease the depth of cut and correspondingly decrease or increase the diameter of that particular part of the arrow 125 shaft. By this means it is possible for the operator to cut arrow shafts which are straight or of uniform cross-section, as indicated in Fig. 9, or tapered toward the head, as indicated at 53^a in Fig. 10 or toward the 130 tail, as indicated at 53^b in Fig. 11, or so-called barrel shaped, as indicated at 53^c in Fig. 12. Notwithstanding this variation in cross-section of the arrow shaft as it passes from the cutter, the steady rest above de-

scribed will at all times maintain a firm centering grip upon the shaft, the jaws 46 yielding resiliently as a larger part of the shaft enters between them, and closing toward the center as a smaller part of the shaft enters between them, the spring 41 always maintaining a definite centralizing pressure on the arrow shaft irrespective of its variation in size.

While I have described my invention as applied to production of arrow shafts, it is also applicable to the production of any shafts or bodies of relatively great elongation and small diameter, requiring support close to the cutting tool.

I claim:

In a shaft forming machine, a work carrier provided with means for receiving, holding and rotating a shaft stock, means for engaging with the shaft stock to feed the same forward in its rotation, a rotary cutter, means for effecting relative motion of the work carrier and rotary cutter, and means adjacent the rotary cutter for supporting the work after it is cut and comprising a stationary support provided with inclined ways converging toward the cutter, jaws movably mounted in said ways and adapted to surround and guide the work, and spring operated means engaging said jaws to move them toward the cutter so as to yieldingly support and guide the work while permitting forward movement thereof.

In testimony whereof I have hereunto subscribed my name this 10th day of November, 1927.

PAUL H. GRANGER.
